(57) **CLAIM**

The ornamental design for a therapeutic gas cylinder bay as shown and described.

DESCRIPTION

FIG. 1 is a top, isometric view of a therapeutic gas cylinder bay, showing our design, wherein oblique line shading indicates a transparent surface;

FIG. 2 is a front elevational view thereof, wherein oblique line shading indicates a transparent surface;

FIG. 3 is a rear elevational view thereof;

FIG. 4 is a right side elevational view thereof, wherein oblique line shading indicates a transparent surface;

FIG. 5 is a left side elevational view thereof, wherein oblique line shading indicates a transparent surface;

FIG. 6 is a top plan view thereof, wherein oblique line shading indicates a transparent surface; and,

FIG. 7 is a bottom plan view thereof.

The broken lines depict portions of the therapeutic gas cylinder bay which form no part of the claimed design.
